UNITED STATES PATENT OFFICE

WALTER H. SCHRUPP, OF GRANITE FALLS, MINNESOTA

RENEWABLE FUSE

Application filed June 15, 1927. Serial No. 199,047.

The present invention relates to improvements in renewable fuses and more particularly to that type of fuse commonly known as tubular fuses and of that character as employed as a protector for telephone systems.

With the usual type of tubular fuse as now employed in connection with telephone systems, the fusible element is soldered at both ends to the metallic ends of the fuse shell or barrel, and thus necessitates that the fuses be returned to a repair shop for the renewing of the fuse when blown.

It is therefore a primary object of the present invention to provide an improved tubular fuse embodying features whereby a new fuse may be readily inserted into the fuse shell and connected with the metallic ends of the shell merely by employment of a wrench or a pair of pliers and thus allowing the fuse to be renewed at its mounting location in a very short time and without requiring that the fuse be transmitted to a repair shop in order that the terminals of the fusible element may be connected with the metallic ends of the fuse.

A further object of the invention is to provide a renewable fuse of the tubular type embodying means whereby the fusible element may be readily inserted through the tubular shell of the fuse and be coupled as by means of suitable nuts to the metallic ends of the fuse.

A further object of the invention is to provide a renewable fuse having metallic heads so constructed and associated with the tubular shell of the fuse as to permit of the fusible element to be readily associated with the fuse without requiring removal of the heads for proper positioning of the fusible element longitudinally within the tubular shell.

A still further object of the invention is to provide a renewable fuse of the tubular type which may be very economically manufactured and one wherein fragmentary portions of the blown fuse element may be readily removed from the tubular shell prior to insertion of the new fuse.

Other objects and advantages of the invention will be apparent during the course of the following detailed description taken in connection with the accompanying drawing

forming a part of this specification and in which drawing:

Figure 1 is a side elevation of the improved renewable fuse.

Figure 2 is a view showing the various elements constituting the fuse and showing the shell and heads of the fuse assembled and in longitudinal section.

Figure 3 is a central longitudinal section through the fuse and showing the fuse wire in position.

Figure 4 is a plan view of the upper end of the fuse as illustrated in Figure 2.

Figure 5 is an end view of the lower end of the fuse as illustrated in Figure 2.

In the drawing, and wherein similar reference characters designate corresponding parts throughout the several views, the improved fuse has been shown as embodying a tubular main body portion or shell 10 which is formed of a suitable insulating material such as fiber or the like, and with the bore of the shell being of equal diameter throughout the length of the shell.

The insulating shell or main body portion 10 is provided with upper and lower metallic ends or heads 11 and 12 respectively, and which heads serve as coupling means for the terminal portions of the fuse wire 13 which is adapted to extend through the tubular shell 10.

The metallic head 11 and which is intended to be connected with the upper end of the shell 10 embodies a plug portion 14 of a diameter to be snugly inserted into the upper end of the shell, and the outer end of the plug portion is provided with an annular flange or shoulder 15 from which extends in axial alignment with the portion 14, an externally screw threaded extension or stem portion 16 of a diameter less than that of the flange 15.

Thus it will be seen that the annular flange 15 forms an annular outwardly facing seat 17 at the inner or lower end of the screw threaded extension 16. As will be observed in Figures 2 and 3, the flange 15 abuts with the upper end of the shell 10 and thus limits inward movement of the head. The head 11 is provided with an axially extending bore 18 which as will be observed extends axially

through the plug portion 14 and extension 16, and this bore is flared into a bell shaped mouth 19 at the inner end of the head with the wall of the mouth terminating in the circumference of the plug portion 14 so that no shoulder or abutment is formed at the inner end of the plug portion such as would prevent ready upward movement of the fuse wire through the bore of the head. The head 11 may be secured in the shell 10 in any preferred manner and in the example shown diametrically arranged pins 20 extend through the shell and plug portion for retention of the head in coupled relation to the shell. The externally threaded extension or stem 16 is provided with a longitudinally extending slot 21 which extends throughout the length of the stem and opens into the bore 18 as is clearly illustrated in Figures 2 and 4. It will be observed that the bore 18 is of relatively large diameter and it may here be well to state that the object in so having the bore 18 as large as possible without weakening the stem 16 to an undesirable degree, will allow for a relatively large opening being formed into the bore of the tubular shell 10 for allowing any fragmentary portions of a blown fuse wire to be removed through the bore 18.

Referring now to the metallic end or head 12 for connection with the opposite or lower end of the shell 10, the same includes a plug portion 22 which is readily insertible into the bore of the shell and is provided at its outer end with an annular flange or shoulder 23 forming an outwardly facing seat 24, and projecting from the seat 24 in axial alignment with the plug 22 is a threaded shank 25. The head 12 may be retained in coupled relation to the shell 10 as by means of suitable diametrically arranged pins 26 which pass through the shell 10 and into the plug portion 22. The inner end of the plug 22 is provided with a flaring pocket 27 provided with a rounded bottom 28. As will be seen, this flaring pocket 27 merges at its mouth portion into the circumference of the plug portion 22, and is of a depth substantially half the length of the plug portion. Extending in angular relation to the axis of the head 12 from the rounded bottom 28 of the pocket 27 to the seat face 24 to one side of the circumference of the shank 25, is a passageway 29 forming communication between the bore of the shell and the head seat 24.

A washer 30 slidably fits over the threaded extension 16 and nuts 31 and 32 are threaded along the extension over the washer 30, while a washer 33 is intended to be slidable over the shank 25 and followed by a clamping nut 34.

When desiring to renew the used wire, the nuts, together with the washers are first removed from the heads 11 and 12 and one end 45 of the fuse wire 13 is inserted through the

passageway 29 and will be guided through the bore 18 of the head 11 by the flaring mouth 19 until the terminal portion which has been inserted through the shell projects for a slight distance past the outer end of the threaded extension 18 and the opposite terminal of the wire extends past the outwardly facing seat 24 of the head 12. The projecting lower end of the wire may then be wound about the shank 25 adjacent the seat 24 in a manner as illustrated in Figures 1 and 3 and then the washer 33 and nut 34 positioned on the shank 25 so that tightening of the nut 34 will firmly clamp the lower terminal of the fuse wire between the washer 32 and seat 24. The upper projecting terminal of the fuse wire is then drawn through the slot 21 and wrapped about the base portion of the threaded extension 16 upon the seat 17 and after which the washer 30 and nut 31 may be applied to the extension for firmly clamping the terminal of the fuse wire between the washer 30 and flange 15. Thus it will be seen that the terminals of the fuse wire are effectively connected with the metallic heads at the opposite ends of the insulating shell 10 without the necessity of soldering the terminals of the wire to the heads, and that no strain is imparted to that portion of the fuse wire extending through the shell during clamping of the terminal portions of the fuse wire to the metallic ends.

It will further be noted that the improved manner of connecting the terminal portions of the fuse wire to the terminal portions of the fuse body does not increase the external diameter of the tubular shell and thus allows for the fuse to be used at locations and installed in a manner as are the tubular fuses now in general use in connection with telephone systems.

From the foregoing description it will be apparent that an improved and novel and renewable fuse has been provided embodying features whereby the fusible element is effectively connected at its end to the terminal portions of the fuse body without the requiring of soldering or special tools for renewing of the elements, and embodying features whereby the fusible element is readily insertible into the carrier body therefor, and one wherein the fragmentary portions of the blown fuse may be easily removed prior to application of the new fuse.

Various changes may be made to the specific form of the invention herein shown and described, without departing from the spirit of the invention or the scope of the following claims.

I claim:

1. In a renewable fuse, a tubular shell, a fuse wire, and a terminal connector for the fuse wire comprising a tubular metallic body providing a longitudinal passageway and having an external annular flange formed

intermediate its ends providing a plug portion for slidably fitting into the bore of the tubular shell and an externally threaded extension slotted throughout its length, said passageway thru the tubular metallic body having a bell shaped mouth at its inner end flaring into the circumferential surface of the plug portion, and retaining means threaded upon the extension for clamping the terminal portion of the fuse wire in engagement with the outer face of the annular flange.

2. In a renewable fuse, a tubular shell, a fuse wire, and a terminal connector for the fuse wire comprising a metallic head including a plug portion for insertion into the bore of the tubular shell and an externally threaded shank portion arranged co-axially of the plug portion and having an annular flange formed at its inner end and providing an outwardly facing annular seat, said plug portion having a flaring pocket opening at its inner end and provided with a rounded bottom, and having a small passageway extending from the base of the rounded bottom in angular relation to the axis of the plug portion and opening upon the annular seat at one side of the threaded shank portion, and means threaded upon the shank portion for clamping the terminal portion of the fuse wire extending thru the tubular shell in engagement with the outwardly facing seat.

3. A renewable fuse comprising a tubular holder of insulating material, a metallic head for the upper end of the holder having an external annular flange providing an outwardly facing annular seat, said head having a relatively large opening axially therethrough provided with a flaring inner end, a metallic head for the lower end of the holder having an external annular flange providing an outwardly facing annular seat, said head having a flaring pocket opening at its inner end and provided with a rounded bottom and having a diagonal passageway extending from the base of the rounded bottom and opening at the annular seat, a fuse wire insertable thru the tubular body thru the head at either end thereof, and means for clamping the terminal portions of the fuse wire in engagement with the outwardly facing head of the head.

WALTER H. SCHRUPP.
